DEVICE FOR USE IN THE ADHESIVE ATTACHMENT OF EDGE BINDINGS TO SHOE PLATFORMS

Charles G. Melanson, Lynn, Mass., assignor to United Shoe Machinery Corporation, Flemington, N. J., a corporation of New Jersey

Application April 22, 1948, Serial No. 22,556

5 Claims. (Cl. 12—17)

1

This invention relates to devices for use in the adhesive attachment of edge covers or bindings to the platforms of platform shoes and it is herein disclosed as embodied in a device wherein an edge binding, such as a strip of pre cemented edge binding material, and a shoe platform are fed by hand past instrumentalities which turn the marginal portions of the strip over and hold them against the pre cemented margins of the upper and lower faces of the platform to cause the margins of the strip to be applied to the margins of the platform. Such a device should provide for the accurate gaging of the platform laterally with respect to the strip and it should also provide for compressing the margin of the platform just prior to and during the application of the strip to insure that the binding will lie taut over the edge face of the platform after completion of the operation.

It is an object of the present invention to provide a simple and inexpensive device for enabling the operation under consideration to be performed under the conditions above outlined. In accordance with a feature of the invention the illustrative device is provided with a guide for the strip and a guide for determining the position of the edge face of a platform laterally with respect to the strip, and with abutments for turning the lateral margins of the strip over and holding these margins against the pre cemented margins of the upper and lower faces of the platform to cause the margins of the strip to adhere to the margins of the platform as the platform is fed under control of the platform guide. As shown herein the platform guide has inclined walls which exert a wedging action to compress the marginal portion of the platform as the platform is forced down into the space between these walls. In accordance with a further feature, the strip guide and the platform guide, as seen in cross section, form guideways which together have the shape of an inverted letter T, the portion which corresponds to the crossbar of the T serving to guide the strip and the portion which corresponds to the stem serving to determine the position laterally with respect to the strip of the edge face of the platform.

These and other novel features of the invention are illustrated in the drawings and are herein-after described and claimed.

Referring to the accompanying drawings,

Fig. 1 is a perspective view of an illustrative device embodying the invention;

Fig. 2 is a longitudinal vertical section of the

2

device showing the position of the work at the beginning of an operation;

Fig. 3 is a perspective view, partly in section, showing the position of the work at an intermediate stage of the operation;

Fig. 4 is a vertical longitudinal section showing the position of the work at a still later stage of the operation;

Fig. 5 is a vertical section taken on the line 10 V—V of Fig. 3;

Fig. 6 is a large scale vertical section taken on the line VI—VI of Fig. 4; and

Fig. 7 is a perspective view of a platform with the edge binding applied thereto.

As shown in the drawings, an oblong rectangular base block 10 has a smooth flat upper surface 12 for supporting a strip S of edge binding material of leather or, if desired, of fabric or other suitable material. The strip S is guided for longitudinal movement on the surface 12 by a pair of thin flat parallel guide members 14 and 16 which engage the lateral edges of the strip, the thickness of the guide members being slightly greater than that of the strip. The guide members 14 and 16 are bridged by a pair of slides 18 and 20 upon which the guide members are secured by screws 22 (Figs. 1 and 3). The slides 18 and 20 engage transverse guideways formed in the block 10 to enable the guide members 14 and 16 to be adjusted laterally to determine the lateral position of the strip S, and they are secured in adjusted position by clamping screws 24 and 26 (Fig. 2) threaded into the respective slides and extending through transverse slots 25 and 27 in the block 10 to permit the lateral adjustment. A platform P, shown as a forepart platform of cork composition, felt, or other resilient material, is gaged laterally with respect to the strip S by a pair of parallel guide members in the form of blocks 28 and 30 which overlie the guide members 14 and 16 respectively and which also extend over the lateral margins of the strip S. The guide block 28 is secured to the base block 10 by a pair of clamping screws 32 which extend through transverse slots 34 in the guide block to permit lateral adjustment of the guide block. In order that such adjustment shall not interfere with the adjustment of the underlying guide member 14, transverse slots 35 (Fig. 5) similar to the slots 34 are provided in the guide member 14 to accommodate the screws 32. The screws 32 are provided with washers 40 to bridge the slots 34. The guide block 30 is similarly secured by screws 42 to the base block 10 with similar provision for lateral adjustment.

The lateral adjustment of the guide members 14 and 16 is made after the screws 32 and 42 have been loosened; then when the slides 18 and 20 have been clamped in their adjusted positions by the screws 24 and 26, the guide blocks 28 and 30 are adjusted to their desired positions and secured by their clamping screws 32 and 42.

Positioned rearwardly (i. e., to the right as shown in Fig. 1) of the guide member 14 and the guide block 28 is an abutment block 44 secured to the base block 10 by a pair of clamping screws 46 which extend through enlarged holes in the abutment block to provide for adjustment laterally and also forwardly and rearwardly, the screws 46 being provided with washers 50 which bridge the enlarged holes. Positioned rearwardly of the guide member 16 and the guide block 30 is an abutment block 52 which is secured to the block 10 by a pair of screws 54 in the manner similar to that which the screws 46 secure the abutment block 44. The guide block 28 and the abutment block 44 are so shaped and adjusted as to provide between them a slot 56 (Fig. 1) of sufficient width to accommodate the thickness of the strip S. This slot slopes upwardly and rearwardly from the upper surface 12 of the base block 10. The guide member 14 terminates rearwardly at the bottom of the slot 56. The guide block 30 and the abutment block 52 are likewise shaped and adjusted to provide between them a slot 58 which is similar to the slot 56. The guide member 16 terminates rearwardly at the bottom of the slot 58. Between the abutment blocks 44 and 52 is a space substantially equal in width to the normal thickness of the marginal portion of the platform P before the strip S has been applied thereto. The abutment blocks 44 and 52 have adjacent walls 60 and 62 (Fig. 6) which are vertical and which engage the lateral margins of the strip S as the strip is being applied to the platform.

The turning of the lateral margins of the strip from their original flat horizontal positions to positions in which they are laid upon the marginal portions of the upper and lower faces of the platform P is accomplished by a pair of abutments 64 and 66. These abutments consist of sloping upwardly diverging oblique conical surfaces formed respectively on the abutment blocks 44 and 52. The abutment 66 (which is shown clearly in Fig. 1) is tangent to and continuous with the sloping front wall of the abutment block 52 (which defines the rear wall of the slot 58) and it is also tangent to and continuous with the vertical wall 62. The abutment 64 (not clearly shown) on the abutment block 44 is similar to the abutment 66.

Between the walls 60 and 62 is an end block 68 which is secured to the base block 10 by a clamping screw 70 extending through a longitudinal slot 72 in the block 68 to provide for forward and rearward adjustment. A washer 74 bridges the slot 72. The block 68 has a forward surface 76 which slopes upwardly and rearwardly from the surface 12 of the block 10, the sloping surface 76 preferably having a slight concave curvature. The sloping surface 76 is positioned rearwardly of the abutments 64 and 66 to leave an open space between the forward portions of the walls 60 and 62.

Between the guide blocks 28 and 30 is a space into which the platform P may be inserted to bring the edge face of the platform into engagement with the strip S. As shown in Fig. 5, the guide blocks 28 and 30 have opposing walls 78

and 80, respectively, which slope downwardly and toward each other to cause somewhat of a compression in the marginal portion of the platform as the platform is pressed down between them, the lower edges of the sloping walls being squared off to avoid cutting into the platform.

The illustrated device, as so far described, can conveniently be made of wood. It can also be made of metal, in which case transverse slots for the screws 22 may be provided in the guide members 14 and 16 to enable these guide members to be adjusted toward and from each other for edge binding strips of different widths. These slots may be rabbeted and bridged by square washers into which the heads of the screws 22 are countersunk. If the device is made of wood, provision for such adjustment is unnecessary, as the screws 22 can be located where desired. Whether the device is of wood or metal, interchangeable end blocks 68 will be necessary to fill the width of the space between the abutment blocks 44 and 52 if these blocks have to be adjusted toward or from each other for platforms of different thicknesses.

In the adjusting of the device, the abutment blocks 44 and 52 are adjusted symmetrically about a longitudinal center line which extends forwardly and rearwardly along the base block 10 and is substantially coincident with the longitudinal center line of the base block. The guide blocks 28 and 30 are adjusted symmetrically about the same center line as the abutment blocks, and just close enough, as shown in Fig. 5, to effect a slight compression of the marginal portions of the platform P as the platform is forced down between the sloping walls 78 and 80. The slides 18 and 20 are adjusted symmetrically with respect to the common center line of the blocks 44 and 52 and of the blocks 28 and 30 if the extent of marginal overlapping of the strip S is to be the same upon the upper and lower faces of the platform P. If, however, a greater or less extent of overlapping is desired upon the upper face of the platform than upon the lower, the guide members 14 and 16 are adjusted the appropriate distances to the right or left of the common center line above mentioned. This adjustment of the guide members 14 and 16, as has already been stated, should be made before the guide blocks 28 and 30 are adjusted and while the screws 32 and 42 are loose.

It will be observed that the guideways for the strip S and the platform P, as seen together in cross section (Fig. 5), are in the form of an inverted letter T with the space between the guide members 14 and 16 forming the cross bar of the T and the space between the guide blocks forming the stem of the T.

Before performance of the operation, the marginal portions of the platform P, as indicated by stippling in the drawings, have been coated with latex or rubber cement all the way to and including the upper and lower corners of the edge face; the edge face itself, however, is left free of cement to avoid the sticking of the strip S to the edge face. The entire surface of that side of the strip S which is to lie next to the platform P is coated with a similar cement. The marginal portions of the outer surface of the strip S may, as indicated by scratch marks, be roughened to facilitate subsequent cement attachment to an upper and an outsole. The marginal portions of the upper and lower surfaces of the platform may have been similarly roughened to facilitate attachment of the strip.

The operation, which is performed manually, consists in threading the strip S, cemented side uppermost, into the space between the guide members 14 and 16, and in then pressing the platform P down between the guide blocks 28 and 30 until the edge face of the platform engages the strip, as shown in Fig. 2. The operator then advances the platform, which frictionally drags the strip S with it, until that portion of the strip which is just under the edge face of the platform is pressed against the surface 16 of the end block 68 and, while thus holding the platform, he turns it through the positions shown in Figs. 3 and 4 until the strip S has been applied to cover the entire edge face of the platform. As the operator turns the platform, the marginal portions of the strip feed up through the slots 56 and 58 and are turned by the abutments 64 and 66 upon the marginal portions of the upper and lower faces of the platform. These abutments, and the walls 60 and 62 which constitute continuations of the abutments, press the marginal portions of the strip against the platform with a pressure resulting from the tendency of the platform to spring back from its compressed state to its initial thickness. This compression was effected by forcing the platform down between the sloping walls 78 and 80 and also by forcing it, with the overlying marginal portions of the strip, past the abutments 64 and 66 and into the space between the walls 60 and 62. The strip does not stick to the uncemented edge face of the platform and, since it was applied while the marginal portion of the platform was under compression, it will lie taut over the edge face after the operation has been completed. The pressure, exerted through the platform, of the strip against the surface 16 of the end block 68 holds the strip smooth against the edge face of the platform and prevents the formation of wrinkles in that portion of the strip which overlies the edge face.

The platform P with the strip S applied thereto is shown in Fig. 7. The ends of the strip may now be trimmed, and the finished article will then be ready to be incorporated in a platform shoe.

Having described my invention, what I claim as new and desire to secure by Letters Patent of the United States is:

1. In a device for use in the adhesive attachment of an edge binding to a shoe platform, a guide engageable with the lateral edges of a strip of pre cemented edge binding material, a guide for determining the position of the edge face of a platform laterally with respect to said strip, said guide having inclined walls for exerting a wedging action to compress the marginal portion of the platform as the platform is forced down into the space between said walls, and abutments for turning the lateral margins of the strip over and holding said margins against the pre cemented margins of the upper and lower faces of the platform to cause the margins of the strip to adhere to the margins of the platform, said abutments being engageable by the strip while the platform is being fed under control of the platform guide and with the margin of the platform under compression.

2. In a device for use in the adhesive attachment of an edge binding to a shoe platform, a guide constructed and arranged to provide a guideway which, in cross section, is in the form of an inverted T, the portion of the guideway which corresponds to the crossbar of the T serv-

ing to guide a strip of pre cemented edge binding material and the portion which corresponds to the stem serving to determine the position, laterally with respect to said strip, of the edge face of a platform, said stem-corresponding portion having inclined walls which, as the platform is forced down into the space between them, exert a wedging action to compress the marginal portion of the platform, and abutments having conical surfaces for laying the marginal portions of the strip over and adhesively attaching them to the pre cemented margins of the upper and lower faces of the platform as the platform and the strip are fed along said guideway and while the margin of the platform is compressed, the result of said compression being to maintain the covering taut over the edge face of the platform after completion of the operation.

3. In a device for use in the adhesive attachment of an edge binding to a shoe platform, a guide engageable with the lateral edges of a strip of pre cemented edge binding material, a guide for determining the position of the edge face of a platform laterally with respect to said strip, abutments for turning the lateral margins of the strip and holding said margins against the margins of the upper and lower faces of the platform to cause the margins of the strip to adhere to the pre cemented margins of the platform as the platform is fed under control of the platform guide, and a member against which that portion of the strip which overlies the edge face of the platform can be held by pressure exerted through the platform while the margins of the strip are being applied to the platform, the purpose of said member being to hold said overlying portion of the strip smooth against the edge face of the platform and thereby to prevent the formation of wrinkles in said overlying portion.

4. In a device for use in the adhesive attachment of an edge binding to a shoe platform, a base block having an upper surface adapted to support a strip of pre cemented edge binding material, a pair of parallel guide members carried by said block for engaging the lateral edges of the strip to determine the lateral position of the strip, a pair of parallel guide members carried by said block for engaging the marginal portions of the upper and lower faces of a shoe platform to determine the lateral position of the edge face of the platform, and a pair of abutments adjacent to the ends of the guide members, said abutments having conical surfaces arranged to turn the lateral margins of the strip over, said abutments having also flat surfaces arranged to hold the lateral margins of the strip against the pre cemented margins of the upper and lower faces of the platform to cause the margins of the strip to adhere to the margins of the platform as the platform and with it the strip are fed under control of their respective guide members.

5. In a device for use in the adhesive attachment of an edge binding to a shoe platform, a base block having an upper surface adapted to support a pre cemented strip of edge binding material, a pair of parallel guide members for engaging the lateral edges of the strip to determine the lateral position of the strip, guide means engageable with the marginal portions of the upper and lower faces of a shoe platform to determine the lateral position of the edge face of the platform, a pair of parallel slides, said block having guideways in which said slides are movable for lateral adjustment, means for securing each of said strip guide members to both of said slides

7
to enable the strip guide members to be adjusted in unison laterally, means for securing said slides in adjusted position, and a pair of abutments adjacent to the ends of the guide members and arranged to turn the lateral margins of the strip over and hold them against the pre cemented margins of the upper and lower faces of the platform to cause the margins of the strip to adhere to the margins of the platform as the platform and with it the strip are fed under control of 10 their respective guide members.

CHARLES G. MELANSON.
